MECHANICAL DISHWASHER

Filed July 27, 1927

UNITED STATES PATENT OFFICE

FORREST A. WALKER, OF SYRACUSE, NEW YORK

MECHANICAL DISHWASHER

Application filed July 27, 1927. Serial No. 208,664.

This invention relates to a mechanical dishwasher of the class set forth in my pending application Serial No. 124,640, filed July 24, 1926, but more particularly to the dish-supporting tray or basket and to a protective screen across the undersides of the dish-supporting members and its relation to the tray and impeller.

These trays or baskets are usually made of open-work wire construction supported within the vat clear from the rotary impeller and provided with an inner cage for receiving and supporting knives, forks, spoons and other small objects in addition to a considerable variety of plates and other dishes commonly used in dining-rooms and kitchens.

One of the objects is to construct the tray or basket with a less number of parts and considerably lighter than has heretofore been practised without sacrificing its strength and durability by making the cage a unitary part of the basket.

Another object is to place a wire screen protective shield within the vat in a plane between the impeller and dish-supporting members and of sufficiently fine mesh to prevent the passage therethrough of knives, forks, spoons and other small objects which, if allowed to pass into the impeller chamber, might cause more or less injury to the impeller or other articles coming in contact therewith.

Other objects and uses relating to specific parts of the apparatus will be brought out in the following description.

In the drawings:

Figure 1 is a top plan of a dish-supporting tray or basket embodying some of the features of my invention including the protective screen.

Figure 2 is a vertical sectional view of the lower portion of a vat with the impeller and dish-supporting tray in operative position.

Figure 3 is an enlarged detail sectional view of a portion of the tray showing the manner of supporting the protective screen on the marginal rail of the tray.

Figure 4 is a side elevation, partly in perspective, of one of the partitions and adjacent portions of the inner and outer rings.

In order that the invention may be clearly understood I have shown a portion of a cylindrical vat —1— of a mechanical dishwasher having an inverted conical bottom —2— and a rotary impeller —3— journaled in the apex 55 of the bottom —2—, said bottom being provided with a drainage outlet —4— at one side of, but adjacent the impeller —3—.

The supporting tray for dishes and other objects previously mentioned is preferably 60 circular in top plan and of approximately but slightly less diameter than the interior diameter of the vat to enable it to be easily inserted and removed through the open top of the vat and comprises an outer marginal 65 guard rail composed of similar wire rings —5— and —5'— arranged in axially spaced parallel relation and held in such relation by posts —6— which are spot-welded or otherwise secured thereto to extend downwardly 70 some distance below the lower ring —5'— to rest upon the upper face of the marginal edge of the bottom —2— of the vat as shown in Figure 2, said posts being arranged in uniformly spaced relation circumferentially 75 considerable distances apart to allow free passage of the washing fluid therethrough.

The rings are also braced against relative axial movement by vertical tie wires —7— which are also arranged in uniformly spaced 80 relation circumferentially midway between the posts —6—.

A pair of vertically spaced wire rings —8— and —8'— of unequal but relatively small diameters are centrally supported upon 85 the inner ends of a series of wire partitions —9— which are arranged approximately tangential to the upper ring —8— with their inner ends in radially spaced relation there- to to permit the insertion of dishes or por- 90 tions thereof edgewise into the spaces.

These partitions are identical in construction and each comprises a pair of substantially horizontal bars —11— and —11'— ar- 95 ranged in spaced relation vertically and hav- ing their inner ends connected by an upright brace wire —12— brazed or otherwise secured thereto and their outer ends similarly brazed or otherwise secured to the upper and lower rings —5— and —5'— so that each 100

partition is supported entirely by the outer rings —5— and —5'— thus cooperating with the brace wire —12— to firmly hold the upper and lower wires —11— and —11'— against relative movement.

- 5 Each wire partition is also provided with a dish-supporting member or wire —13— disposed in a plane below the lower wire —11'— and having its outer end united to the upright wire —12— and its inner end secured to the lower wire ring —8'— radial thereto to extend across the intervening space between the inner end of the partition and rings —8— and —8'— and therefore at an angle to the vertical plane of the wire portions —11— and —11'— to enable portions of the dishes to rest edgewise thereon during the washing and rinsing operations.

As illustrated the wire portions 11, 12 and 13 of each partition are made in one piece, the inner end of the lower portions 13 being continued upwardly and outwardly at 14 to form with the parts 12 and 13 a loop for receiving the adjacent edges of the dishes while the opposite ends of the part 11' of each partition are secured respectively to the upright portion 12 and to the ring 5' (see Figure 4).

20 The junctions of the parts 13 and 14 are secured to the ring 8', while the upper ends of the parts 14 are secured to the ring 8.

25 The rings 8 and 8' together with the upright portions 14 form a supplemental central basket as clearly shown in Figures 1, 2 and 4.

It will be noted upon reference to Figure 35 1 that the upper and lower wire portions —11— and —11'— are disposed in vertically inclined planes at an angle to each other nearly tangential to the upper ring —8—, the upper wire portions —11— being offset from the vertical plane of the lower portions —11'— to facilitate the reception and retention of concavo-convex dishes between the partitions and to assist in holding them in more or less similar relation to the screen bottom —15— and rings —8— and —8'— when resting edgewise upon the wire portions —13— between the outer rings —5— and —5'— and inner rings —8— and —8'—.

30 A wire screen —15— of sufficiently fine mesh to prevent the passage of knives, forks, spoons and other small objects therethrough is supported in a horizontal plane between the impeller —3— and dish-supporting members —13— of the several wire partitions —9— to extend across the entire area of and beneath the super-posed outer rings —5'— and —8'— for the purpose of preventing the passage of the smaller articles therethrough into the impeller chamber which might stop or damage the impeller and articles coming in contact therewith.

35 The outer marginal edge of the screen —15— is permanently secured by spot welding or otherwise to a marginal ring —16— similar to, but somewhat heavier, than the

rings —5— and —5'—, said screen being further reinforced against sagging at the center by an additional ring —17— spot welded or otherwise secured thereto concentric with, but in spaced relation to, the ring —16—.

70 The ring —16— with the screen —15— thereon is supported from the lower ring —5— by means of a circumferential series of small hangers —18— preferably of thin sheet metal having their upper ends provided with eyes hinged to the ring —5'— in uniformly spaced relation circumferentially and their lower ends provided with hooks —19— movable into and out of engagement with the ring —16— so that when the dish-supporting tray or basket with the screen —15— thereon is removed from the vat —1—, the screen —15— may be removed from the tray by simply detaching the hooks —19— from the ring —16—, said hooks being sufficiently opened at the top to permit the wire 16 to pass therethrough.

75 The dish-supporting tray is similar in some respects to Patents 1,496,957, June 10, 1924, and No. 1,426,931, August 22, 1922, in so far as the broad idea of tangential rings is concerned but differs therefrom in the construction of the bottom of the basket and in the use of an underlying protective screen between the impeller and dish-supporting members and also in the construction of the supporting means for the central cage in which knives, forks and spoons are adapted to be placed.

Operation

100 When placing the dishes and other articles in the dish-supporting tray or basket the latter is preferably withdrawn from the vat —1— and allowed to rest upon a work-table or other support, the dishes being then placed edgewise vertically between the partitions —9— to rest against the same sidewise and upon the underlying wire portions —13— while the knives, forks and spoons will be placed in a separate receptacle preferably perforated, not shown, but adapted to be placed within the rings —8— and —8'— to be supported thereby during the washing operation.

105 When the tray is filled with dishes and other articles to be washed, it, together with the screen —15— on the lower side thereof, will be placed within the vat so that the lower ends of the posts —6— will rest upon the upper face of the marginal edge of the conical bottom —2— under which conditions the dish-supporting tray and screen will be entirely clear from and above the impeller —3—.

110 The rotation of the impeller will circulate the water upwardly and circumferentially in the manner described in my pending application above referred to for effecting a thor-

ough washing and cleansing of the dishes in the tray.

It is evident, however, that two or more similar trays may be supported within the receptacle in planes one above the other without departing from the spirit of this invention.

The use of the horizontal screen —15— in a plane between the impeller and dish-supporting partitions —9— is particularly useful in connection with the type of impeller shown in my pending application Serial No. 208,665, filed July 27, 1927, in that the washing fluid is impelled upwardly and circumferentially in more or less the form of an inverted cone and when impinged against the screen is broken up into infinite number of streams which, however, maintain their upward projection by reason of the lifting force of the impeller, the resultant effect of which is to produce a more even distribution of the water to the overlying dishes in the tray or trays, it being understood that the circumferential motion of the water is maintained until the desired diagonal impact of the water with the dishes is established at which time the dishes deflect the water in various directions and allows said water to fall back into the bottom of the vat through the intervening spaces between the dishes and the interstices in the screen.

What I claim is:—

In a mechanical dishwasher, an open-work dish-supporting tray having outer lower and upper marginal rings and inner lower and upper marginal rings, the inner and outer rings being arranged about a common axis in radially spaced relation, and partition wires connecting all the inner and outer rings across said space and having portions thereof depressed to form loops for receiving adjacent edges of the dishes to assist in holding the latter edgewise vertically.

In witness whereof I have hereunto set my hand this 21st day of July, 1927.

FORREST A. WALKER.
